UNITED STATES PATENT OFFICE.

ROBERT E. STIPES, OF TOLEDO, OHIO, ASSIGNOR OF ONE-HALF TO
ADAM CHRISTMAN, OF TOLEDO, OHIO.

NON-REFILLABLE BOTTLE.

No. 798,712.

Specification of Letters Patent.

Patented Sept. 5, 1905.

Application filed April 13, 1905. Serial No. 255,280.

To all whom it may concern:

Be it known that I, ROBERT E. STIPES, of Toledo, county of Lucas, and State of Ohio, have invented certain new and useful Improvements in Non-Refillable Bottles; and I do hereby declare that the following is a full, clear, and exact description of the invention, which will enable others skilled in the art to which it appertains to make and use the same, reference being had to the accompanying drawings, and to the figures of reference marked thereon, which form part of this specification.

My invention relates to means for preventing the refilling of bottles after the liquid contents have been removed therefrom. In carrying out the same I employ certain novelties of construction and the combination and arrangement of parts hereinafter shown, described, and claimed.

In the accompanying drawings, illustrative of my invention, Figure 1 is a sectional view showing the arrangement of the various parts. Fig. 2 shows the altered position of the parts in dotted outline when the bottle is inverted or tilted to remove the contents. Fig. 3 is a sectional plan view on line *xx*, Fig. 1, of the auxiliary neck of the bottle. Figs. 4 and 5 are detached views of parts hereinafter referred to.

Referring to the drawings, 1 is a bottle having the enlarged tapered neck 2; 3, a centrally-perforated or annular cork fitted in the bottle-neck; 4, a tube open at its upper end and closed at its lower end, said tube being inserted and held by friction in the central perforation in the cork 3; 5, a valve-orifice through the wall of the tube 4; 6, a sleeve adapted to slide upon the tube 4 to open or close the valve-orifice 5; 7, flanges upon the sleeve 6, adapted to retain glass or porcelain balls 8, loosely interposed between the sleeve and the bottle-neck; 9, an enlargement at the lower end of the tube 4 to limit the downward movement of the sleeve 6; 10, an auxiliary neck, grooved or crimped, as shown at 11, Fig. 3, to provide inclined passage-ways for liquid in its side walls and cemented or otherwise secured against removal to the neck 2; 12, a supplemental valve member constructed of glass, having the hollow stem 13 and the expanded upper portion 14, resting upon the annular cork 3; 15, a disk of cork or other buoyant material disposed upon the member 12, and

16 a ball normally resting upon the disk 15 and having a limited movement within the auxiliary neck 10.

The relation of the various parts when assembled is shown in Fig. 1.

The filling of the bottle is accomplished before the parts are placed in position. After the bottle has been filled the annular cork 3, carrying the tube 4, together with the balls 8, is placed in position in the bottle-neck. The supplemental valve member 12, 65 the cork disk 15, and the ball 16 are inclosed by the auxiliary neck and the latter firmly cemented to the bottle-neck. To remove the liquid contents, the bottle is tilted, as shown in Fig. 2, causing the sleeve 6 to slide along 70 the tube 4 and also causing the supplemental valve 12 to be unseated. The liquid will then pass through the orifice 5 and the tube 4, around the supplemental valve 12, and through the passages in the auxiliary neck, 75 emerging finally from the mouth of the neck. Upon again returning the bottle to its upright position the parts will resume the position in Fig. 1, the sleeve 6 being assisted in returning to its position at the lower end of 80 the tube 4 by the added weight of the balls 8 engaging the marginal flange upon the sleeve. It will be observed that the expanded head of the supplemental valve member 12 takes a position between the annular cork 3 and the 85 cork disk 15 and is therefore reasonably secure from breakage, the disk above the same protecting the valve member from violent contact with the ball 16. It is apparent that the bottle cannot be refilled while in upright position. Should an attempt be made to refill the bottle by immersing it in inverted position in a tub or other receptacle containing liquid, the buoyancy of the cork disk 15 will press the supplemental valve member 90 against the annular cork and prevent the passage of the liquid into the bottle, the action being assisted by the buoyancy of the supplemental valve member owing to the hollow stem with which it is provided. Direct access to the supplemental valve and the cork disk thereon is prevented by the ball contained within the auxiliary neck.

From the foregoing description of my invention it will be seen that I provide novel 105 and effective means for preventing the unscrupulous refilling of bottles.

Having described my invention, what I

claim, and desire to secure by Letters Patent, is—

1. The combination in a bottle of an annular cork in the bottle-neck, a tube supported by said annular cork having a valve-orifice, a sleeve adapted to slide upon said tube to open or close said valve-orifice, a supplemental valve member seated upon said annular cork to normally close said tube, a float adapted to force said supplemental valve member against said annular cork when immersed in inverted position in a liquid, and an auxiliary neck inclosing said supplemental valve and float, substantially as described.
- 15 2. The combination in a bottle of an annular cork in the bottle-neck, a tube supported by said cork, open at its upper and closed at its lower end and having a valve-orifice, a sleeve adapted to slide upon said tube to open and close said valve-orifice, flanges upon said

sleeve, balls engaging said sleeve-flanges to assist in sliding the same along said tube, a supplemental valve having an expanded head to seat upon the annular cork to normally close the upper end of said tube, a float co-acting with said valve to close said tube when said valve and float are immersed in inverted position in a liquid, a ball resting upon said float, and an auxiliary neck provided with passages for liquid in its side walls, adapted to inclose said supplemental valve, float and ball, substantially as described. 25 30

In testimony that I claim the foregoing as my own I affix my signature in presence of two witnesses.

ROBERT E. STIPES.
